UNITED STATES PATENT OFFICE.

STEFANO SANTILLI, OF CANTON, OHIO.

PARING AND SLICING KNIFE.

Application filed October 2, 1926. Serial No. 139,101.

This invention relates to paring knives and more particularly to a knife for paring and slicing potatoes.

The objects of the improvement are to provide a knife which is easily and readily adapted for paring potatoes or the like in varying thicknesses and also for slicing the potatoes; a curved pointed blade being provided upon the end of the knife for cutting out eyes and the like from the vegetable.

The above and other objects may be attained by providing a triangular core upon a suitable handle, cutting blades being located parallel to the various faces of the triangular core and spaced at varying distances therefrom to provide for cutting parings of different thickness or slicing the pared potato in slices of different thickness.

An embodiment of the invention is illustrated in the accompanying drawing, in which—

Figure 1 is a side elevation of the improved paring knife, and

Fig. 2, a transverse section taken substantially on the line 2—2, Fig. 1.

Similar numerals refer to similar parts throughout the drawing.

The improved knife comprises a handle portion 1 formed of any suitable material and having a triangular core 2 connected to one end thereof.

This core may be formed of any desired material and is preferably of aluminum and formed integrally with the handle and provided at its ends with flanges 3, 3^a and 3^b of varying thicknesses.

The blades 4, 4^a and 4^b are connected at

their ends to these flanges by screws 5, or their equivalents.

Each blade is thus spaced from and parallel with the adjacent face of the triangular core 2, the several blades being located at different spaced distances from the adjacent faces of the core.

As best illustrated in Fig. 2, each blade is preferably located adjacent to one corner of the triangular core with its cutting edge 6 disposed toward the next adjacent corner.

The core thus acts as a guard to control the thickness of the paring to be taken from the potato or the thickness of the slice to be cut therefrom.

By turning the knife in the hand any desired face of the triangular core may be brought into proper position for paring or slicing the potatoes in the desired manner.

For the purpose of removing eyes, dark spots and the like from the potato, a curved blade 7 may be formed upon the end of the triangular core opposite to the handle 1.

I claim:

1. A knife comprising a core portion provided with a plurality of faces, flange portions of different thicknesses at the ends of said faces, and cutting blades secured to said flanges and parallel with said faces.

2. A knife comprising a core portion provided with a plurality of flat faces, flange portions of different thicknesses at the ends of said faces, and cutting blades secured to said flanges and parallel with said faces.

In testimony that I claim the above, I have hereunto subscribed my name.

STEFANO SANTILLI.
